Primary Examiner — Dana Meyrow(74) *Attorney, Agent, or Firm* — Gerard J. McGowan, Jr.(57) **CLAIM**

We claim the ornamental design for a bottle, as shown and described.

DESCRIPTION

FIG. 1 is a perspective view from above and the right of our bottle.

FIG. 2 is front elevational view of our bottle.

FIG. 3 is a rear elevational view of our bottle.

FIG. 4 is a side elevational view of our bottle from the left side.

FIG. 5 is a side elevational view of our bottle from the right side.

FIG. 6 is a top plan view of our bottle; and,
FIG. 7 is a bottom plan view of our bottle.

The broken lines in the drawings illustrate the portions of the bottle that form no part of the claim.

1 Claim, 5 Drawing Sheets# US D875,537 S
